ABSTRACT

A low-power, regulated, high-impedance current source wherein a saturable or square loop core is used to control the current in an inhibit winding of a ferrite core-type computer memory circuit.

SATURABLE LOOP CORE CURRENT SOURCE

BACKGROUND OF THE INVENTION

In the field of computer memory circuits of the ferrite core type current in an "inhibit" winding is used to prevent the change of state of a particular core due to the current in a "write" winding. The values of these currents must be closely controlled so that an accidental change of state of a particular core does not occur. The control of these currents is usually accomplished by a sophisticated transistor regulator circuit. Since one regulator circuit is required per inhibit winding in a core matrix, this approach is initially expensive, increases the power needed to operate the computer memory, and the reliability of the computer memory is reduced as active elements are employed in the regulator circuit.

It is an object of this invention to eliminate the need for a separate transistor regulating circuit for each "inhibit" circuit in a core matrix.

It is another object of this invention to provide a regulating circuit which returns at least a portion of the energy employed during operation to the power supply.

Still another object of the present invention is to provide a regulating circuit having a minimum number of active components.

These and other objects of the present invention will become apparent from the following description.

SUMMARY OF THE INVENTION

The present invention provides a low-power, regulated, high-impedance circuit for control of the current in the inhibit winding of a core type memory. The regulator employs a saturable or square loop core transformer as the control element.

DESCRIPTION OF THE DRAWING

The FIG. is a schematic diagram of the regulator circuit of the present invention.

DESCRIPTION OF THE PREFERRED EMBODIMENT

As seen in the drawing, the main elements of the regulator include the inhibit winding W_4 , transformer T_1 , saturable core transformer T_2 , transistor Q_1 , and the plus and minus 15-volt power supplies (not shown).

In operation, a bias current I_2 is applied to the winding W_5 of the saturable core transformer T_2 via L_1 . The magnitude of the bias current is such that saturation of one leg of the core of T_2 is maintained. When a current is to be applied to the inhibit winding W_4 , the transistor Q_1 is driven into conduction by an appropriate control signal applied to the base of Q_1 . The current I_1 begins to flow and the flux generated thereby cancels the flux in the core of T_2 generated by the bias current I_2 . As the currents I_1 and I_2 become equal, the core of T_2 comes out of saturation because the flux in the core is now near zero. When the core of T_2 comes out of saturation, it begins to ex-

hibit a high permeability and the reactance of the winding W_4 limits the current I_1 to a value that balances out the bias current I_2 . Since I_1 also flows through T_1 , a current is induced in the W_1 winding of T_1 and hence in the inhibit winding W_4 . By selecting proper component values, this balance condition can be made the regulated current level of the pulse current desired in the inhibit winding W_4 . When current is no longer desired in the inhibit winding, the control signal applied to the base of Q_1 is removed, Q_1 becomes nonconductive and the current I_1 goes to zero. Simultaneously the energy that is stored in the saturable core of T_2 is restored to the -15-volt power supply via C_{R3} , W_6 , and C_{R1} , C_{R2} and W_2 restore the energy stored in the inhibit winding and the transformer T_1 to the +15-volt power supply. Hence most of the reactive energy built up in the magnetic fields of the transformers during the operation of the regulator is returned to the power supplies, thereby improving the efficiency of the regulator. Since I_1 is now zero, the bias current I_2 drive the core of T_2 back into saturation and the circuit is capable of repeating the above described cycle.

It is understood that the foregoing disclosure relates only to the preferred embodiment of the present invention and any modifications obvious to one skilled in the art, which do not depart from the spirit and scope of the invention as set forth in the following claims, are deemed to constitute a part of this disclosure.

What is claimed is:

1. A high-impedance current-regulating circuit for controlling the current in the inhibit winding of a ferrite core memory matrix and a power source for energizing said circuit comprising:

first transformer means for inducing a control current in the inhibit winding of the core matrix;

second transformer means of the saturable core type serially connected to the first transformer means for regulating the current in the first transformer means;

bias means connected to the second transformer means for maintaining the core of said second transformer means in a saturated condition;

transistor means serially connected to the second transformer means for controlling the flow of current in said second transformer; and

energy restoring means for restoring the energy in the magnetic field of the transformer back to the power source.

2. A regulating circuit as defined in claim 1 wherein the serial connection between the first and second transformer means joins the input windings of the first transformer means to the input winding of the second transformer means such that regulation of the current in the second transformer means also regulates the current in the first transformer means.

3. A regulating circuit as defined in claim 1 wherein said transistor means is serially connected to the input winding of said second transformer means for initiating and stopping the current in said winding.
